ELECTRICAL COIL WINDING DEVICE

Bismark C. Beitling, San Fernando, Calif.

Application October 30, 1933, Serial No. 695,885

11 Claims. (Cl. 140—92.2)

This invention is an improvement of the invention filed by me March 24th, 1933, and bearing Serial Number 662,413 (Patent No. 1,948,875, dated February 27, 1934) and entitled Electric coil winding apparatus, and has for its prime object, the same purpose and intention as the above referred to co-pending application, and, in addition thereto, has for a further object unified and simplified control and refinement in exactitude of operation, with the result that electrical coils may be wound with a greater degree of man efficiency and a greater degree of exactness than has heretofore been possible.

In the drawings, two (2) sheets:

Figure 1 is a utility view showing the coil winding device mounted on a power driven mandril ready for use, coils are shown in the position they would occupy during the winding operation.

Figure 2 is a plan view of the device shown in Figure 1.

Figure 3 is a sectional elevation taken on line 3—3, Figure 2, showing construction of the end posts and operative means thereof.

Figure 4 is a view partially in section, of the post shown in Fig. 3.

Figure 5 is a transverse sectional elevation of the post shown in Figures 3 and 4.

Figure 6 is a detail taken on line 6—6, Figure 2, showing cross arm construction.

Figure 7 is a detail taken on line 7—7, Figure 6, showing cross arm and post construction.

Figure 8 is a detail, principally in section, showing construction designed to provide end post rotation stop limits.

Figure 9 is a transverse section taken on line 9—9, Figure 8, showing the end post rotation stop limits in elevation.

Figure 10 is a plan view in section, showing end post construction.

Figure 11 is a view in elevation of the device shown in Figure 10.

Figure 12 is a longitudinal sectional elevation showing interior construction and detail.

Figure 13 is a detail taken on line 13—13, Figure 12.

Figure 14 is a detail showing the interlocking means designed to operatively connect or disconnect the cross arms operating means.

Figure 15 is a detail taken on line 15—15, Figure 14, showing in elevation, the structure illustrated in Figure 14.

Figure 16 is a detail of one of the fingers used on the end posts.

Figure 17 is a sectional elevation showing in detail the construction employed in the end posts.

Figure 18 is a fragmental plan view showing the gear and rack driving means adapted to rotate the posts on the cross arms.

Figure 19 is a sectional elevation showing construction illustrated in Figure 18.

Figure 20 is a detail of one of the end posts showing the spring means adapted to return the rack to normal inoperative position.

The device of this invention essentially comprises a channeled base member 25 which is adapted to be fitted with cross arms 26 from which adjustable posts 27 are adapted to extend. End posts 30 are adjustably secured to the base member 25 and are in co-operative relation to the posts 27.

As shown in Figures 3, 9, 12 and 17 of the drawings, the channeled member 25 is formed with longitudinally extending grooves which are fitted with racks 32 and 33, which are adapted to transmit power to the several operating parts herein.

A crank, 34 is rotatably mounted in the medial vertical center of the base member, its shaft 35 being fitted with gears 36 and 37 which are adapted to engage and drive the racks 32 and 33 back and forth in the grooves 31.

The end 39 of the shaft 35 is journaled in the transverse section 40 of the base 25 by means of a screw stud 41.

The base 25 is fitted with spaced liners 45 which are screwed to the inner faces of the channeled base 25. The lower faces of the liners are stepped to receive and hold the end posts 30.

The finger supporting posts 30 are movably placed on the base 25 and each post is adapted to be rotated through 180 degrees and to be longitudinally moved through a limited range, the extent of such movement being dependent upon the size of the coil to be wound.

As shown, particularly in Figure 17, the posts 30 are formed in two sections, the upper section 44 being fitted to a base member 45 which rests upon the channeled base 25 and is, as previously mentioned, adapted to both rotate within and slide over the upper surface of the base 25.

A flange 47 secured to the base member 45 gives stability to the post as well as forming a means to grip the base 25 as occasion may require, as will be hereinafter described.

The base members 45 of the posts 30 are formed with a reduced section 49 which is snugly fitted between the opposing faces of the liners 45, thus adding to the lateral stability of the posts 30.

Immediately below the above referred to reduced section, the base member 45 is again reduced in section and is fitted with a collar 52 which is securely fitted thereto and is adapted to fit between the opposing faces 53 and 54 of the stepped configuration of the liners 45.

Being at a point immediately adjacent to the lower face of the collar 52, the remaining portion of the base member 45 is threaded to receive a nut 54 having a flange 55.

The nut 54 is adapted to rotate upon its thread-

ed support, through a predetermined arc, the limits of which are determined by the following circumstances: (1) Contact between the nut 54 and its flange 55, and the collar 52, (2) the engagement of pin 57, see Figures 10 and 11, secured in collar 52 with pin 59 secured in the flange 55 of nut 54.

The purpose of this partial rotation will be hereinafter described.

10 The exterior of the nut 54 is provided with a few heavy threads upon which a second nut 62 is adapted to rotate.

15 The nut 62 is provided with a gear 63 which is formed integral therewith and which is adapted to engage one of the racks 32 or 33. As shown in Figure 17, the gear 63 is engaging rack 33 and is rotated thereby when the rack is advanced or retracted.

20 There are two posts 30, one adapted to be operated by rack 32, while, as above stated, the other is operated by rack 33.

End post construction:

25 A vertically movable rack 65 is adapted to move upwardly and downwardly within the posts 30.

30 The lower end of the rack 65 rests against the inner and upper face 66 of the nut 62, a ball bearing 67 interposed between the end of the rack 65 and nut 62, tends to reduce friction to a minimum. A spring 68 is placed in the upper extremity of the longitudinal passage 65' within which the rack 65 operates.

35 The spring 68 bears against the upper end of the rack while the opposite end of the spring abuts a plug 70 which is screwed into the upper end of the passageway 65'. The spring 68 forces the rack downwardly against the face 66 of the nut 62 at all times when the racks 32 and 33 and gears 63 are not actuated.

40 As shown in Figures 8 and 17 the rack 65 is adapted to oscillate a stem 70' by means of a gear 71 which is fitted onto the end of the stem 70' which is journalled in a bearing 73 which is held in position by means of a bushing 74 screwed into the post 30.

45 The stem 70' is formed with a cross member 76 upon each of which a pair of fingers 77 are adjustably fitted as is clearly shown in Figure 17. Figure 16 shows the inner face of one of the fingers and clearly shows a shallow 78 which is dimensioned to equal one half of the diameter of the stem 70' so that the fingers 77 may be brought together to any degree in order to accommodate various sized wires or coils. The fingers are held in position by means of set screws 80.

55 Having thus described the construction of the channelled base and of the end posts, I will now describe the construction of the cross members and the posts used in connection therewith.

60 As shown in Figures 3 and 6, the exterior of the base member 25 is formed with longitudinally extending V shaped slots 85 which are designed to accommodate guides 86 which are secured to the under surface of the cross arms 26 to keep the arms aligned through their travel distance.

65 As shown in Figures 2, 6, 7, 18 and 19 the cross arms 26 are also formed of channelled metal and, as previously stated, are held in slideable relation to the base member 25 by means of the guides 86 operating in the V slots 85.

70 The cross arms 26 are routed to accommodate racks 90 and 91. Each rack being opposite the other and in the same transverse plane.

75 The racks 90 and 91 are driven back and forth substantially as are the racks 32 and 33, however,

the power necessary to move the racks 90 and 91 is derived from the motion of racks 32 and 33, by means of gears 94 and 95, each of which are driven by but one of the racks 32 and 33.

That is, gear 94 is driven by rack 32. The gear 94 is secured upon a stem 97 which is provided with a circular flange 98, spaced above the gear 94 and which is adapted to rest against the stepped faces of the liners 46. An extension 99 of the stem 97 rests upon the bottom web 40 of the base member 25, thereby keeping the gear in constant mesh with its rack.

That portion of the stem 97 which enters the cross arm 26 is of reduced section and is fitted within a sleeve 100, upon which a gear 102 is fitted and which is in mesh with racks 90 and 91.

As shown in Figure 15, the sleeve 100 is provided with a slot 104 through which a pin 105 extends to engage one end face of a cam 107 which is formed on the upper face of gear 102.

20 A bushing 109 keeps the sleeve 100 centrally aligned in a block 110 which rests between the opposing sides of the channelled cross arms 26 and which also rests upon liners 111 which are fitted to the inner faces of the cross arm.

25 As shown in Figure 19 the reduced section of the stem 97, while for the purpose of driving gear 102 is continuous with the section of the stem 97 which carries gear 94, nevertheless, the upper, or reduced section 97' of the stem 97 is physically separated therefrom.

30 The lower end of stem section 97' is squared and is fitted into a square recess 113 in stem 97 so that when gear 94 and stem 97 rotate stem section 97' also rotates and carrying pin 105 with it causes the sleeve 100 and gear 102 to also rotate for the reason that the end 114 of the pin 105 engages an end face of cam 107, forcing the cam and gear to rotate.

35 The lower end of stem section 97' is squared and is fitted into a square recess 113 in stem 97 so that when gear 94 and stem 97 rotate stem section 97' also rotates and carrying pin 105 with it causes the sleeve 100 and gear 102 to also rotate for the reason that the end 114 of the pin 105 engages an end face of cam 107, forcing the cam and gear to rotate.

40 If it is desired to disengage gear 102 from racks 90 and 91 it is only necessary to pull upwardly on stem section 97' as indicated by dotted lines in Figure 15, to lift the gear 102 from engagement with racks 90 and 91 for the reason that pin 115 is carried with stem section 97' and bears against the lower face of gear 92 when it is lifted upwardly, thereby lifting the gear 102 from engagement with racks 90 and 91.

45 The posts 27 are adjustably fitted in the cross arms and are adapted to move in response to movement of racks 90 and 91.

50 The posts 27 are rotatably mounted in frames 120 and 121. As shown in Figures 18 and 19, the frames are identical in construction, that is, each have parallel top and bottom pieces 122 and 123 which are joined together by end blocks 125 and 126.

55 The end of post 27a is fitted with a half gear 130 that is adapted to engage and to be meshed with rack 90.

60 Post 27b is journalled in frame 121 and has its end fitted with a full gear 133 which is in mesh with a second full gear 134.

65 A half gear 135 is formed in the same stock from which gear 134 is cut, and is adapted to engage and to be meshed with rack 91.

70 The lower ends of posts 27a and 27b are journalled in bottom pieces 124, while full gear 134 and half gear 135 are journalled in bottom piece 123a.

75 Having thus described the physical construction of the invention herein disclosed, I will now set forth the interdependence of the several features herein included and its operation in general.

Assuming that the coil winding device has pre-

viously been set for winding a coil, substantially as indicated in Figures 1 and 2.

With the machine thus set up, the free end of the spool wire from which the coil is to be wound, 5 is given a temporary loop around one of the fingers 77, as shown in Figure 1. The power mandril is then driven by a source of power not shown, and, as the device is rotated a plural number of turns of wire are laid between the fingers 10 of the first group 77. After the necessary number of turns are laid down the continuing spool wire is directed by hand to the next pair of fingers 77a, where the preceding operation is repeated, after which the spool wire is directed to 15 the finger group 77b, where the preceding operation is again repeated.

For the sake of reasonable limitation, only three finger groups are shown; it will be apparent that there may be more, or less, and that the spacing 20 between fingers, which limit the width of the coil may be varied for the reason that the fingers 77 are laterally adjustable, as shown in Figure 17.

When the coil is wound and it is desired to remove it from its supporting frame, it is only necessary to turn the crank 34 clockwise, or in the direction of arrow "A"; this action rotates gears 36 and 37.

Since the action to be now described applies equally to both cross arms as well as to both end posts, there would be no point gained in repetitious discussion, and for that reason the action of one end post and one cross arm will be described, for, as above stated, the other cross arm and end post simultaneously function as the one now to be described.

The rotation of gear 36 in a clockwise direction, 40 retracts rack 32 and rotates gear 63 on nut 62, causing the nut to be advanced on its threaded support, which, of course, is nut 54. This action applies pressure to the bottom of rack 65 and causes it to move upwardly and by so doing, rotates gear 71, finger stem 70, and fingers 77, 77a and 77b.

This action carries through about 90 degrees and is designed to give the ends of the coils a twist.

Continued rotation of nut 62 drags nut 54 also in a clockwise direction causing it to unwind from the threaded stem 49, thus releasing the pressure with which flanges 55 and 47 had previously gripped the upper and lower faces of the liner 45, due to having been previously forced upwardly.

The nut 54 and flange 55 continue to rotate 50 clockwise until stud 59 in flange 55 engages stud 57 in collar 52, which causes the whole post 30 to revolve clockwise until the fingers 77 are pointed inwardly and in position to release the coil just formed.

Simultaneously with the foregoing operation, gear 94 is also partially rotated by reason of the retraction of racks 32 and 33, thus, rotating stem 97 and stem section 97' which, in turn, causes pin 105 and pin end 114 to engage on end face of cam 107, thereby dragging gear 102 and causes racks 90 and 91 to move through their grooved ways.

From the foregoing it will be apparent that retraction of rack 32 causes gear 94 to move clockwise, thus causing rack 90 to be also retracted, or to move in the direction of the arrow "B", see Figure 14.

Retraction of rack 90 rotates half gear 123 in 75 a clockwise direction and turning fingers 140 on

posts 27 inwardly as indicated by dotted lines, see Figure 2.

Rack 91 is also retracted by the rotation of gear 102, thus partially rotating half gear 135 and proportionately rotating full gear 134. Gear 134 is in geared connection with full gear 133 which, in turn, is connected to the lower end of post 27b. The above described double gear is employed to cause fingers 141 to rotate in a counter-clockwise direction instead of clockwise, thereby causing all of the fingers to be turned inwardly to permit easy removal of the coils 150 from their supporting frame.

In ordinary practice, a plural number of coils of the same size are wound, thus it is not necessary to change the positions of the posts 30 and 25 27, and arms 26 very frequently; however, it will be necessary to change the setup from time to time.

When it is necessary to change the position 20 of the posts 30 it is only necessary to turn the crank 34 to the right or left, as the case may be, in order to cause the posts 30 to move outwardly or inwardly to meet the requirement of overall length or distance between end posts, 25 which distance will, of course, vary with the length of the coil to be wound.

If the length of the parallel sides of the coil is to be increased or decreased, it is only necessary to pull the stem section 97' upwardly as 30 indicated by dotted lines, see Figure 15. This action causes pin 105 to bear against the under surface of gear 102 and to lift it from meshed engagement with rack 90. The cross arms 26 can then be forced by hand pressure, either 35 outwardly or inwardly over the upper surface of the base 25 in proportion to the size of the coils to be wound.

If it is desired to wind square coils, it is only necessary to pull stem section 97' upwardly to 40 disengage gear 102 from rack 90. The crank 34 can then be turned counter clockwise until posts 30 are freed from their position in the base member 25.

In order to limit the rotation of end post 45 30 to 180 degrees, stop motion studs 150' are inserted in posts 30, and move through operative positions substantially as shown in Figure 8.

This position corresponds with the position of the posts when a coil is being wound on the 50 device. When the coil is to be removed and the post 30 is turned 180 degrees, the stud 150' swings through cut away section 152 until rotated through 180 degrees, at which time the stud 150' will bear against face 153 of liner 45, 55 such contact will stop rotation of the post 30, thereby aligning the fingers 77 in an inwardly position that coincides with the longitudinal center of base 25.

The converse of this action is also true, for 60 stud 156 prevents post 30 from passing beyond the longitudinal center of base 25 when fingers 77 are moved outwardly to receive the windings of a new coil.

While the above described motion stop limits 65 are not shown as applied to posts 27, the inclusion of such stop limits will be apparent from their application to end posts 30.

Having thus described the preferred form of my improvement in electrical coil winding devices, I do not wish to be known as limiting the scope of my invention to the specific form herein disclosed, but include all such variations of features of construction as clearly fall within the scope of the invention herein shown.

- I claim:
1. In a coil winding device, a base, posts supported on said base, cross arms supported on said base, posts on said cross arms, coil spacing fingers on said posts, means to partially rotate said posts and certain of said fingers and means to retract said posts, said means being a plural number of gears and racks in operative relationship.
  2. In a coil winding device, a base, posts supported on said base, cross arms on said base, a post adjacent to the end of each of said cross arms, means to partially rotate said posts, means to retract said posts, said means being a plural number of gears and racks in operative relation.
  3. A coil winding device, comprising a base, movable posts adjacent to the ends of said base, cross arms, movable posts on said cross arms and means to synchronously rotate all of said posts, said means being a plural number of gears and racks, and manual means to operate said gears and racks to manipulate said posts.
  4. A coil winding device comprising a base, movable posts adjacent to the ends of said base, cross arms, movable posts on said arms and means to operatively actuate said posts, said means comprising racks in said base, means to move said racks, gears meshed with said racks to actuate first said movable posts, racks in said cross arms, said last mentioned racks being driven by said first mentioned racks, and gears on the posts on said arms, said gears and cross arm posts being actuated by the racks in said cross arms.
  5. In combination with a coil winding device having end posts and cross arms having posts, means to operatively actuate said end posts, said means comprising movable racks in the base of said device, fingers on said end posts, and means, operable by said racks, to actuate said fingers prior to rotation of said end posts; a second set of racks, said last mentioned racks being movable in response to movement of first said racks, fingers on the posts of said cross arms to align and support wires to be wound into a coil, said fingers being primarily actuated by the racks in said base member.
  6. In a coil winding device, a base, a movable finger supporting posts adjacent to each end of said base, racks in said base, means to actuate said rack, vertically extending racks in said posts, said last mentioned racks being actuated by the racks in said base, means interposed between the racks in said posts and said fingers whereby said fingers will be given a rotatory motion in response to movement of the racks in said base, cross arms in slidable relation to said base, finger supporting posts on said cross arms, racks in said cross arms, means operatively connecting the racks in said base and in said cross arms, and means operatively connecting the posts on said arms with the racks in said cross arms whereby actuation of the racks in said base will actuate all of said finger supporting posts.
  7. The combination, in a coil winding device of a base, movable arms on said base, and of a plurality of movable posts on said base and arms, of means to actuate certain of said posts prior to others of said posts, said means comprising a vertically movable rack, extending substantially through said pinion gears driven by said
- rack, fingers in rotatable relation to said gears, a threaded stem on the ends of said posts, a rotatable nut, adapted to be screwed onto said stem and to lift said rack when said nut is advanced further on said stem.
8. The combination, in a coil winding device of a base, movable arms on said base, and a plurality of movable posts on said base and arms, of means to actuate certain of said posts prior to others of said posts, said means comprising threaded stems on the ends of said posts, a nut adapted to advance or be retracted on said stem, a rack extending vertically through said posts and adapted to be lifted when said nut is advanced, pinion gears journaled in said post and in driven relation to said rack coil supporting and forming fingers in direct rotating relation to said rack, and power racks to advance or retract said nut.
9. The combination, in a coil winding device of a base, movable arms on said base and a plurality of movable posts on said base and cross arms, of means to actuate certain of said posts prior to others of said posts, said means comprising threaded stems on the ends of said posts, a nut adapted to advance or be retracted on said stem, racks extending vertically through said posts and adapted to be lifted when said nut is advanced on said stem, pinion gears journaled in said posts and in driven relation to said racks, coil forming and supporting finger operated by said pinion gears, power means to advance or retract said nut and spring means to force said rack to normal position when said nut has been retracted.
10. The combination, in a coil winding device having a base, movable arms on said base and a plurality of movable finger supporting posts on said base and arms, of means to actuate the fingers on the posts on said base, prior to retraction of said posts and means to retract said post, last said means comprising a threaded section on said posts, a collar on said post, a nut on said post, a second nut, said second nut being adapted to be threaded upon said first mentioned nut, means to rotate said second nut to effect partial rotation of said first mentioned nut, and lugs, one of said lugs being on said collar, the other of said lugs being on the first of said nuts, whereby rotation of said first mentioned nut and its associated lug will effect contact with said collar and its associated lug to effect rotation of said collar and post.
11. The combination, in a winding device having a base, movable arms on said base, a plurality of rotatable and retractable finger supporting posts on said base, means to actuate said fingers, means to advance and/or retract said posts, and means to rotate and advance and/or retract the posts on said arms, racks in said arms, a half gear on one of said posts, said half gear being in mesh with one of said racks, the other of said cross arm posts being fitted with a full gear, a second full gear in mesh with first said full gear, said second full gear having a half gear integral therewith, said last mentioned half gear being in mesh with the other of said racks, whereby moving said racks will cause one of said posts to rotate in a clockwise direction, the other of said posts to rotate counter clockwise.

BISMARCK C. BEITLING.
